UNITED STATES PATENT OFFICE

96,998

DESIGN FOR A TEXTILE FABRIC OR SIMILAR ARTICLE OF MANUFACTURE

Kalman I. Ostow, Brooklyn, N. Y., assignor to Concord Fabrics, New York, N. Y., a copartnership composed of Kalman I. Ostow and Louis Kalman

Application July 9, 1935, Serial No. 57,576

Term of patent 3½ years

To all whom it may concern:

Be it known that I, Kalman I. Ostow, a citizen of the United States, residing in Brooklyn, county of Kings, city and State of New York, have invented a new, original, and ornamental Design for a Textile Fabric or Similar Article of Manufacture, of which the following is a specification, reference being had to the accompanying drawing, forming a part thereof, and showing a face view of a piece of textile fabric embodying my design.

I claim:

The ornamental design for a textile fabric or similar article of manufacture substantially as shown.

KALMAN I. OSTOW.
